DESIGN FOR A GEM MOUNTING

Marianne Ostier, New York, N. Y.

Application January 5, 1949, Serial No. 76

Term of patent 7 years

(Cl. D45—1)

To all whom it may concern:

Be it known that I, Marianne Ostier, citizen of the United States of America, residing at New York, in the county of New York and State of New York, have invented a new, original, and ornamental Design for a Gem Mounting, of which the following is a specification, reference being had to the accompanying drawing, forming part thereof.

In the drawing

Fig. 1 is a top plan view of a gem mounting embodying my new design.

Fig. 2 is a side view partially in section along the lines 2—2 of Fig. 1, and

Fig. 3 is a similar view partially in section along the lines 3—3 of Fig. 1.

I claim:

The ornamental design for a gem mounting, as shown.

MARIANNE OSTIER.
